UNITED STATES PATENT OFFICE.

SAMUEL E. LIGHT, OF LEBANON, PENNSYLVANIA.

SECTIONAL STEAM-GENERATOR.

SPECIFICATION forming part of Letters Patent No. 655,252, dated August 7, 1900.

Application filed December 20, 1899. Serial No. 740,990. (No model.)

To all whom it may concern:

Be it known that I, SAMUEL E. LIGHT, a citizen of the United States, residing at No. 22 North Tenth street, Lebanon, in the county 5 of Lebanon and State of Pennsylvania, have invented certain new and useful Improvements in Sectional Steam-Generators; and I do hereby declare the following to be a full, clear, and exact description of the invention, 10 such as will enable others skilled in the art to which it appertains to make and use the same. My invention relates to steam-generators, has especial reference to that class known as "sectional," in which the headers are connected by water and fire tubes, has for its 15 object economy in construction and a high degree of efficiency as a steam-generator; and it consists in certain improvements in construction, which will be fully disclosed in the 20 following specification and claims.

In the accompanying drawings, which form part of this specification, Figure 1 represents a front elevation, partly in section; Fig. 2, a side elevation, partly in section; Fig. 3, a vertical section and a side view of one of the headers on an enlarged scale; and Fig. 4, a side elevation of one of the headers and tubes connected therewith, parts thereof being shown in section.

Reference being had to the drawings and the letters thereon, A indicates the headers, serpentine in form, to be closely nested, and in each alternate neck a is formed a transverse partition b to divide the header into 35 separate chambers c and the partitions serving to stiffen or brace the headers, so that the fire-tubes need not be permanently or rigidly secured thereto by swaging, caulking, or upsetting, as is the usual practice. On the outer 40 side of each header are openings d, internally screw-threaded to receive externally-screw-threaded packing-boxes e, having a packing-chamber f to receive asbestos or other suitable packing, (not shown,) and a gland g, connected thereto by a screw-threaded connection, and opposite each opening d is an opening h, slightly less in diameter than the opening d, to admit of removing the tube secured in the opening h through the opening d should 45 said tube require renewing, and around each opening h is a projecting wall i, forming a chamber k to receive a suitable packing, (not

shown,) and on each end of the header is an opening l, also surrounded by a wall m, forming a packing-chamber n.

The water-tubes B are connected to the headers through the medium of the openings h, and the fire-tubes C pass concentrically through the tubes B and are secured to the headers by the glands g, so that they are 60 free to expand and contract and can be readily replaced when necessary without unnecessary labor or waste of time, and the partitions b stiffen the headers, so that there is no vibration therein produced by the expansion 65 and contraction of the tubes.

The headers at the front or rear end of the boiler are connected at their lower ends by nipples or in any preferred manner to a water-distributing pipe D and the upper ends are 70 connected by nipples p or in any preferred manner to a steam-distributing pipe E, and the steam-distributing pipe is connected to a plurality of small steam-drums F by pipes q, so that a high degree of pressure of the steam 75 may be carried in the drums at the minimum of danger of explosion, and the circulation of the water in the boiler is rendered direct by the tubes B and C connecting the chambers c of the front and rear headers, so that the 80 water flows from one chamber to another throughout the headers.

The circulating-pipes D and E are connected by pipe G, T's H and I, and an expansion-joint K, and water is supplied through pipes 85 r, extending down through T's H, pipes G, and T's I, where it is heated and is discharged into chambers s, rises through filter-chamber t, and is distributed through pipe D into the several headers A and passes on in circulation through the water-tubes B into the several chambers c in the headers and is converted into steam, which is first collected in pipe E, from which it rises into the drums F and is conducted therefrom by pipe u, thence 90 through valve v and suitable conduits or pipes to the place of consumption.

The drums F are supported at their front end by the pipe D and at their rear end by a truss or beam L, supported on columns M 100 and yokes or stirrups w, connected to the beam L.

Having thus fully described my invention, what I claim is—

1. A header having screw-threaded openings on one side thereof, screw-threaded packing-boxes engaging said openings and provided with externally-screw-threaded packing-glands engaging said packing-boxes, and openings on the other side of the header opposite said former openings and of less diameter than the packing-boxes, and openings at each end of the header.
- 10 2. A serpentine header having opposite openings arranged in pairs, transverse partitions between each pair of openings, screw-threaded openings on one side of the header provided with detachable packing-boxes, adjustable packing-glands connected to said boxes, and openings at each end of the header.
- 15 3. A serpentine header having openings arranged in pairs, a transverse partition between each pair of openings and forming separate chambers, detachable packing-boxes in each chamber on one side of the header, and openings on the opposite side of the header of less diameter than the packing-boxes, and openings at each end of the header.
- 20 4. A steam-generator having serpentine headers at each end provided with openings arranged in pairs, a transverse partition be-

tween each pair of openings and forming separate chambers in the headers, detachable packing-boxes in each chamber, and openings 30 opposite thereto, fire-tubes connected to the headers by said packing-boxes and their glands and extending through the headers, and water-tubes connected to said opposite openings in the headers and surrounding the 35 fire-tubes.

5. A steam-generator having serpentine headers at each end provided with openings arranged in pairs, a transverse partition between each pair of openings and forming separate chambers in the headers, detachable packing-boxes in each chamber, and openings 40 opposite thereto, water and steam distributing pipes to which the headers are connected, fire-tubes secured in said packing-boxes 45 to expand therein and extending through the headers, and water-tubes surrounding the fire-tubes and connected to the headers.

In testimony whereof I affix my signature in presence of two witnesses.

SAMUEL E. LIGHT.
